UNITED STATES PATENT OFFICE.

FRANK N. ROEHRICH, OF JERSEY CITY, NEW JERSEY, ASSIGNOR, BY DIRECT AND MESNE ASSIGNMENTS, OF FOUR-FIFTHS TO WILLIAM H. LOUD AND ONE-FIFTH TO HENRY J. LAUDA, BOTH OF JERSEY CITY, NEW JERSEY.

KEY LOCK.

Original application filed January 26, 1927, Serial No. 163,643. Divided and this application filed October 19, 1927. Serial No. 227,071.

This invention relates to key-operated locks, and more particularly locks of the general Yale type; the object of the invention being to provide simple and efficient means which permits the ready manual insertion and operation of the key, yet is effective automatically to eject the key from the keyway of the lock when the key is manually released at the conclusion of the 10 operation.

The invention comprises the combination with a lock, including a rotary actuating element having a keyway therein, of a spring-pressed key ejector which is movable with- 15 in and longitudinally of the keyway.

The invention also comprises novel features of construction and combinations of parts which will be hereinafter described; the scope of the invention being then defined 20 in the appended claims.

In the drawings—

Figure 1 is a transverse vertical section of a lock embodying a form of my invention, showing the key as inserted and the 25 ejector as pushed back from the keyway preparatory to the turning of the key.

Fig. 2 is a similar view upon the completion of the locking operation, showing the ejector as shot into the keyway and indi- 30 cating a portion of the ejected key.

Fig. 3 is a vertical section adjacent the back of the lock casing, as on the line 3—3 of Fig. 1.

Fig. 4 is a similar section through the 35 guide extension of the rotary barrel of the lock, as on the line 4—4 of Fig. 1.

Fig. 5 is a similar section of the lock through the casing and barrel, as on the line 5—5 of Fig. 1.

The type of lock herein illustrated em- 40 bodies a fixed cylindrical body 10, and a rotatable barrel 11 therein formed with a key- way 12 arranged eccentrically of the barrel, which body and barrel are provided with a series of relatively arranged spring-pressed 45 plungers, 13, which normally lock the barrel to the fixed body, yet are movable into unlocking relation by the action against the free ends of the respective plungers, of the appropriately formed edge of a key, as 14, when the key is forcibly inserted in the key- 50 way. Thereupon, by the manipulation of the key the barrel can be turned to the

right or left to effect the actuation in relation to a suitable keeper, of a latching or locking element operatively connected with the barrel.

According to my present invention, in its preferred form, the inner end of the barrel 11 is formed with a hollow extension 55 15 having its bore in longitudinal alignment with the keyway of the barrel, and an ejector bar 16 of appropriate cross-section is slidably arranged in the bore and keyway. A suitable spring 17 confined in the bore 60 15 presses against a head 18 on the inner end of the bar 16 and tends to maintain the bar normally within the keyway throughout substantially the entire length of the latter. Hence, coincidentally with the insertion of 70 the key in the keyway and the consequent release of the lock barrel by the action of the key against the opposing plungers, the bar 16 is bodily pushed back into the extension against the force of the spring 17, 75 as seen in Fig. 1, thereby permitting the turning of the barrel by means of the key in the usual manner. This done, if the key be manually released, the spring, expanding, will press the bar 16 quickly forward in 80 a manner to eject the key from the lock, thus obviating any liability of the careless leaving of the key in the lock by the user. The lock barrel 11 is preferably provided at its inner end with a projecting pin 19 85 to which and to an adjacent part of the structure on which the lock is mounted, is attached a suitable retracting spring 20 which tends normally to return the barrel to key-receiving position.

In the present instance the lock body 10 is represented as mounted in the transmission housing 21 of an automobile for example, and the locking element comprises a lever 22 which is adapted by actuation of 95 the barrel to be moved into and out of locking engagement with the apertured lug 23 of a gear shift lever 24.

The lever 22 has a hub 25 which is rotatably seated in a bearing formed in the adjacent wall of the housing concentric with the barrel 11, which hub encircles the extension 15 of the barrel. A cap 26 on the outer end of the hub bears against the adjacent wall of the housing and maintains 100 105 the locking lever in proper relation to the

lock barrel. Extending through the wall of the hub 25 and into the path of the eccentric extension 15 is a pin 27 against which the extension abuts during its rotation with the lock barrel and thereby moves the pin 27 and the locking lever in a manner to disengage the latch arm from the keeper 23 of the gear shift lever.

The locking lever 22 may be held in un-
locked position against the action of a suit-
ably-disposed spring 28 by means of a mov-
able restraining arm 29 which is operable by
connections under the joint control of the
seat and door of a car, as described in Let-
ters Patent of the United States No. 1,675,-
465, dated July 3, 1928, of which this applica-
tion is a division.

While I have herein shown and described
my invention as applied to a key-actuated
lock for use in connection with an essential
control element of an automobile, it is to be
understood that my invention may be em-
ployed in connection with a lock for any
purpose. Moreover, my invention is not
limited to the specific form of mechanism
herein illustrated, as the same may be modi-
fied within the principle of the invention
and the scope of the appended claims.

I claim—

30 1. The combination with a lock, includin-
a rotary actuating element having a keyway

therein eccentrically thereof, and a guide ex-
tension in alignment with the keyway, of
a key ejector movable within and longitudi-
nally of the extension and keyway, a spring 35
pressing said ejector normally toward the
outer end of the keyway, a locking member
adjacent the rotary element, means main-
taining said locking member normally in
locking position, and means on said locking 40
member engageable by the extension to move
the locking member to releasing position.

2. The combination with a lock, includ-
ing a rotary actuating element having a key-
way therein eccentrically thereof, and a 45
guide extension in alignment with the key-
way, of a key ejector movable within and
longitudinally of the extension and keyway,
a spring pressing said ejector normally to-
ward the outer end of the keyway, an oscil-
latory locking member mounted concentri-
cally of the rotary element and encircling
the extension, means maintaining said lock-
ing member normally in locking position,
and means on said locking member engage-
able by the extension to move the locking 50
member to releasing position.

Signed at Jersey City, in the county of
Hudson and State of New Jersey, this 8th
day of October, A. D. 1927.

FRANK N. ROEHRICH.
